DESIGN FOR LACE

William H. Woodhouse, Hightstown, N. J.

Application July 19, 1935, Serial No. 57,731

Term of patent 3½ years

To all whom it may concern:

Be it known that I, William H. Woodhouse, a citizen of the United States of America, residing in Hightstown, county of Mercer, and State of New Jersey, have invented a new, original, and ornamental Design for Lace, of which the following is a specification, reference being had to the accompanying drawing, forming part thereof, wherein.

The figure is a plan view of a piece of lace showing my new design, and shows the design unit included within the dot and dash lines.

I claim:

The ornamental design for lace, substantially as shown and described.

WILLIAM H. WOODHOUSE.
